[57] CLAIM

The ornamental design for a set of grips for bicycle handlebars, as shown and described.

DESCRIPTION

FIG. 1 is a perspective view looking downwardly at the

top, right side and front of the righthand grip of the set of grips for bicycle handlebars embodying my new design;

FIG. 2 is a perspective view looking upwardly at the bottom, left side and back thereof;

FIG. 3 is a top plan view thereof;

FIG. 4 is a front elevation thereof;

FIG. 5 is a side elevation as seen from the left of FIG. 4;

FIG. 6 is a side elevation as seen from the right side of FIG. 4;

FIG. 7 is a back elevation thereof;

FIG. 8 is a bottom plan view thereof;

FIG. 9 is a cross-section taken in the direction of the arrows on line 9—9 of FIG. 3;

FIG. 10 is a perspective view looking downwardly at the top, left side and front of the lefthand grip of the set of grips for bicycle handlebars;

FIG. 11 is a perspective view looking upwardly at the bottom, right side and back of FIG. 10;

FIG. 12 is a top plan view of FIG. 10;

FIG. 13 is a front elevation of FIG. 10;

FIG. 14 is a side elevation as seen from the right of FIG. 13;

FIG. 15 is a side elevation as seen from the left of FIG. 13;

FIG. 16 is a back elevation of FIG. 10;

FIG. 17 is a bottom plan view of FIG. 10;

FIG. 18 is a cross-section taken in the direction of the arrows on line 18—18 of FIG. 12.

Fig. 9.
